DESIGN FOR A GAME BOARD

Frank H. Dean, Stockton, Calif., assignor of sixteen and one-third per cent to A. A. Cree, sixteen and one-third per cent to H. J. Goff,
and sixteen and one-third per cent to E. O.
Setzer, all of Stockton, Calif.

Application May 6, 1940, Serial No. 92,184

Term of patent 7 years

To all whom it may concern:

Be it known that I, Frank H. Dean, a citizen of the United States, residing at Stockton, in the county of San Joaquin and State of California, have invented a new, original, and ornamental Design for a Game Board, of which the following is a specification, reference being had to the accompanying drawing, forming a part thereof.

The figure is a plan view of a game board showing my new design.

The board is of no material or substantial thickness.

I claim:

The ornamental design for a game board, as shown and described.

FRANK H. DEAN.
